COMBINED ELECTRIC STOVE AND
IRONING DEVICE

Ada A. MacDonald, Ithaca, N. Y.

Application March 2, 1934, Serial No. 713,723

11 Claims. (Cl. 219—19)

This invention relates to electrical appliances and more particularly to a combined electric heating and ironing device.

The object of the invention is to provide a combined heating and ironing device of simple and durable construction especially adapted for use by seamstresses, dressmakers, tailors and others for pressing out seams, tucks, hems and other portions of a garment or for ironing lace, doilies, or similar delicate fabrics and which may be readily converted into a stove when it is desired to cook or heat liquids or different kinds of foods.

A further object of the invention is to provide a device of the character described capable of being quickly attached to a sewing machine table or other support so as to be in convenient reach of a seamstress using the same and which will always be ready for immediate use thereby enabling the seamstress to press seams or other portions of a garment without the necessity of stopping work and heating the ordinary domestic sad-iron usually employed for this purpose.

The invention has for a further object the provision of a combined heating and ironing unit mounted for pivotal movement and so constructed that, when it is swung downwardly on its pivot to a horizontal position, it may be used for ironing purposes and when swung upwardly to a vertical position may be used as a stove.

The invention further contemplates the provision of a cylindrical casing or jacket surrounding and mounted for rotation on the heating unit and constituting an ironing surface on which fabric may be placed and efficiently ironed or pressed without danger of scorching or otherwise damaging the fabric.

A still further object of the invention is generally to improve this class of devices so as to increase their utility, durability and efficiency.

In the accompanying drawings, forming a part of this specification, and in which like numerals of reference indicate corresponding parts in all the figures of the drawings,

Figure 1 is a perspective view of a combined stove and ironing device embodying the present invention showing the same in position on a sewing machine table and ready for ironing purposes.

Figure 2 is a vertical sectional view of Figure 1 showing in dotted lines the heating unit swung upwardly to vertical position and used as a stove for heating or cooking purposes.

Figure 3 is an end view of a heating unit with the ironing surface removed and showing the

construction of the heating element at the outer end of said unit,

Figure 4 is a side elevation of the inner core detached showing the manner of positioning the coils for heating the ironing surface,

Figure 5 is a transverse sectional view taken on the line 5—5 of Figure 2.

The improved combined ironing device and stove, forming the subject-matter of the present invention, comprises a bracket 5 adapted to extend over the edge of a sewing machine table or other suitable support 6 and provided with an inwardly extending arm 7 in which is threaded a clamping screw 8, the inner end of which is adapted to bear against the bottom of the table 15 and firmly secure the bracket in position thereon. The bracket 5 is provided with spaced upstanding ears 9 and fitted between said ears are arms 10 of a substantially U-shaped base support, indicated at 12. Interposed between the arms 10 and the base support is a spacing sleeve 13 and extending through said sleeve and likewise through the arms 10 and ears 9 is a bolt 14 which forms a pivotal connection between the bracket and base 12, said bolt being provided 25 with a wing nut 15 by means of which the base may be clamped in different positions of adjustment with reference to the supporting bracket. Threaded in the closed end of the support 12 is a rod or shaft 16 having a terminal recess or 30 socket 17 in the outer end thereof and adapted to receive a centering boss or bearing 18 extending inwardly from the adjacent end of a cylindrical jacket or casing 19 constituting an ironing surface. The inner end of the casing 19 is cut 35 away to form a stop shoulder 20 defining a circumferential flange 21 and engaging said flange and shoulder and retained in position by screws 20' is a ring or collar 22 which bears against an end plate 23 forming a stationary closure for the 40 inner end of the casing 19. It will, of course, be understood that in actual practice there will be sufficient space between the end plate 23 and ring 22 to allow for expansion and contraction of the casing 19 when the latter is heated. The 45 end plate 23 is threaded on the rod 16, as indicated at 24, and also bears snugly against the base support 12 so that the casing and base support will move as a unit around the pivot bolt 14.

The peripheral edge of the plate 23 is cut away to 50 receive the ring or collar 22 and said cut away portion defines a guide rib 23 which bears against the inner face of the ring 22 so as to form a guide for the casing 19 during the rotation thereof.

Secured in any suitable manner to the rod 16 is a cylindrical core 26 formed of porcelain, bakelite, isinglass or other suitable insulating material, and the walls of this core are provided with spaced longitudinally disposed grooves 27 in which are seated heating coils 28 of standard construction. The coils 28 are connected in series and the terminals 29 of the wires constituting the coils are connected with a suitable socket plug 30 seated in the end plate 23 and also of standard construction. The plug 30 coacts with a mating plug 31 secured to an electric conductor 32, the plug 31 being provided with a standard cut-off switch 32' so that by opening the switch and inserting the prongs of the plug 31 into the sockets of the plug 30 the heating coils may be connected in an ordinary house circuit for effecting heating the device. If desired, however, the plug 30 may be omitted and the terminals of the coils extended through suitable openings in the end plate 23 for connection with any suitable source of electric current. As previously stated, the coils 28 are for the purpose of heating the revolving casing 19 when the device is used for pressing or ironing fabric. In order to heat the end or top 33 of the casing 19, when the device is swung upwardly and used for heating or cooking purposes, the adjacent end of the core 26 is formed with a substantially spiral groove 34 in which is seated a supplemental heating coil 35, the terminals of which are connected with an auxiliary plug 36 similar in construction to the plug 30. It will be noted that the rod 16, core 26, and end plate 23 are stationary while the casing 19 is free to revolve around the same, being guided in its rotary movement by the centering boss 18 and the collar or ring 22 bearing against the peripheral edge of the end plate 23 and this rotary movement of the casing 19 serves to prevent accidental scorching or damaging of fabrics when said fabrics are placed on the ironing surface of the casing and a reciprocating motion imparted thereto to effect the ironing thereof.

In operation, the device is positioned on a table or other suitable support by passing the arm 7 of the bracket beneath the support and tightening the clamping screw 8, as best shown in Figure 2 of the drawings. When the device is to be used for ironing or pressing seams, hems, tucks, or other portions of a garment, or for ironing collars, handkerchiefs, or other delicate fabrics, the clamping nut 15 is loosened and the heating element swung downwardly to the horizontal position, shown in Figure 1 of the drawings, and in which position it may be firmly secured by tightening said nut. It will be obvious that by placing the goods to be pressed on the ironing surface of the casing 19 and imparting a slight reciprocating movement to the goods the seams of the garment will be effectually pressed and, inasmuch as the casing is free to rotate on the core, liability of concentration of the heat at any particular point on the periphery of the casing and consequent scorching or other damage to the fabric is effectually eliminated. It will, of course, be understood that after the device is swung downwardly to a horizontal position, the prongs of the plug 31 will be introduced within the sockets of the plug 30 so that the coils 28 will be connected in the house circuit and heating of the coils and ironing surface thereby effected.

When it is desired to use the device for heating water, coffee, or other commodities, the screw 15 is loosened and the heating unit swung upwardly

to the dotted line position shown in Figure 2 of the drawings, after which the wing nut 15 is tightened so as to hold the heating unit in an upright position and in which position the top 33 of the casing may be used as a support for a vessel containing the liquid or food to be heated. When the heating unit is used as a stove, the plug 31 will be removed from the socket 30 and inserted in the socket 36 so that the supply of current to the coils 28 will be automatically cut off and the coils 35 heated to supply the necessary heat for cooking purposes.

In some cases it may be found desirable to employ a switch of standard construction connected with the heating coils for cutting out one or more of the coils thereby to vary the degree of heat.

It will, of course, be understood that the devices may be made in different sizes and shapes and constructed of any suitable material and supplied with any number of heating coils without departing from the spirit of the invention.

From the foregoing description, it is thought that the construction and operation of the device will be readily understood by those skilled in the art and further description thereof is deemed unnecessary.

Having thus described the invention, I claim:

1. A device of the class described comprising a supporting bracket, a base pivotally connected with the bracket, a rod connected with the base and provided at one end thereof with a socket, a core mounted on the rod and provided with grooves, heating elements seated in the grooves in the core and operatively connected with a source of electric current, and a casing rotatably mounted on the core and provided with an inwardly extending centering stud seated in said socket, said casing constituting an ironing surface.

2. A device of the class described comprising a core, heating elements seated in the core and operatively connected with a source of electric supply, a rod extending through the core and provided with a socket, a head secured to the rod at one end of the core, a casing surrounding the core, a collar secured to the casing and bearing against the head, and a centering stud extending inwardly from the casing and fitted in said socket.

3. A device of the class described comprising a core, a rod extending through the core, a head threaded on said rod, heating elements engaging the side walls of the core and having terminals extending through said head for connection with a source of electric current, other heating elements seated in one end of the core and having terminals extending through the head for connection with an electric circuit, a casing surrounding the core and provided with a cut-away portion defining a stop shoulder, and a ring fitted in the cut-away portion of the casing and bearing against said shoulder and the periphery of the head.

4. A device of the class described comprising a supporting bracket having upstanding ears, a substantially U-shaped support pivotally mounted on said ears, a spacing member interposed between the arms of the support, a rod engaging the support and provided with a terminal socket, a head threaded on the rod, a core surrounding the rod, main and auxiliary heating coils carried by the side walls and one end of the core, respectively, and provided with terminals accessible through said head, a casing surrounding the core and mounted for rotation thereon and provided

with a centering stud fitting in the socket in the end of the rod, said casing and core being movable on said supporting bracket to either a vertical or horizontal position, and means for holding the parts in either of said positions.

5. A device of the class described comprising a support, a heating element pivotally mounted on the support and movable from a vertical position to a horizontal position, means for securing the heating element in a selected adjusted position, means for connecting the heating element in an electric circuit, and a casing surrounding the heating element and mounted for rotation thereon, the casing having side walls constituting an ironing surface, and an end portion disposed uppermost when the heating element is vertical and constituting a rest for a cooking utensil.

6. A device of the class described comprising a support, a heating element pivotally mounted on the support for movement to vertical and horizontal positions, said element being provided with heating coils extending longitudinally thereof along its sides and other heating coils extending transversely thereof at its outer end, a casing surrounding the heating element and mounted for rotation about the same, the casing having annular walls constituting an ironing surface when the heating element is horizontal and a head at its outer end constituting a support for a cooking utensil when the heating element is vertical, means for connecting the heating coils in an electric circuit, and means for holding said element in different positions of adjustment.

7. A device of the class described comprising a heating element having side and end heating coils, a casing mounted for rotation about the heating element and having annular side walls constituting an ironing surface and a flat head at its outer end serving as a rest for a cooking utensil when the heating element and casing are disposed vertically, a support, a pivotal connection between the support and the inner end of the heating element whereby the heating element may be swung from a horizontal position to a vertical position, means for selectively connecting the heating coils in an electric circuit, and means for holding the heating element in different positions of adjustment.

8. A device of the class described comprising a core provided with seating grooves in its side faces and outer end face, heating elements seated in said grooves, means for selectively connecting the heating elements in an electric circuit, a casing surrounding the core and mounted for rotation thereon and having annular side walls constituting an ironing surface when the core is disposed horizontally and a head at its outer end constituting a support for a cooking utensil when the core is disposed vertically, a supporting bracket, a base at the inner end of the core, and a clamping screw extending through the base and

bracket to pivotally mount the core for swinging movement from a horizontal position to a vertical position and hold the core in different positions of adjustment.

9. A device of the class described comprising a bracket for attachment to a support, a base pivotally connected with the bracket for swinging movement in a vertical plane from a vertical position to a horizontal position, a rod secured to and movable with the base, a core mounted on the rod and provided with seating grooves in its side faces and outer end face, heating elements seated in the grooves, means for connecting the heating elements in an electric circuit, and a cylindrical casing surrounding the core and mounted for rotation thereon, said casing having annular side walls constituting an ironing surface heated by the heating elements in the side grooves of the core and at its outer end having a head heated by the heating elements in the grooves of the outer end of the core and constituting a support for a cooking utensil when the casing and core are in a vertical position.

10. A device of the class described comprising a core pivotally mounted to assume either a vertical or horizontal position and having longitudinal seating grooves in the side walls thereof and auxiliary grooves in the outer end of the core, heating coils seated in the longitudinal grooves, other heating coils seated in the auxiliary grooves, means for connecting either set of heating coils in an electric circuit, means for holding the core in either a vertical or horizontal position with the outer end of the core uppermost when vertical, and a casing surrounding the core and mounted for rotation thereon, the casing having cylindrical walls constituting an ironing surface and having a head at its outer end formed with a flat outer face and constituting a support for a cooking utensil when the casing and core are in a vertical position.

11. A device of the class described comprising a support, a rod pivotally mounted on the support and adjustable with respect thereto from a vertical position to a horizontal position, a core carried by said rod, longitudinal and transverse heating coils carried by the core and countersunk in the side faces and outer end face thereof, means for selectively connecting either the longitudinal or transverse coils in an electric circuit, a rotatable casing surrounding the core and having side walls constituting an ironing surface and a head at its outer end, and means for securing the rod, core and casing in a selected adjusted position, the longitudinal coils serving to heat the side walls of the casing when the core is in horizontal position and the transverse coils serving to heat the head of the casing when the core is in a vertical position.
